UNITED STATES PATENT OFFICE.

WILLIAM KEARNS, OF DETROIT, MICHIGAN, ASSIGNOR TO MORGAN & WRIGHT, A CORPORATION OF MICHIGAN.

MACHINE FOR TREATING RUBBER.

1,277,729.

Specification of Letters Patent.

Patented Sept. 3, 1918.

Application filed July 17, 1917. Serial No. 181,002.

To all whom it may concern:

Be it known that I, WILLIAM KEARNS, a citizen of the United States, and a resident of Detroit, county of Wayne, and State of Michigan, have invented certain new and useful Improvements in Machines for Treating Rubber, of which the following is a full, clear, and exact description.

My invention relates to machines for treating rubber, and more particularly to a calendering machine especially adapted for use in the production of tread stock for vehicle tires.

The product of machines heretofore used has been characterized by inequalities in the gage of the stock and in the density thereof, with resultant absence of uniformity in the weight of the tread. Furthermore, there were present at times surface imperfections, such as waves and wrinkles on the surface of the stock, and there was a tendency toward imperfections in the stock due to the imprisonment of air within the body of the plastic composition.

A machine made in accordance with my invention is so constructed that the rubber stock before passing between some of the calendering rolls, and after it has been brought approximately to gage, will be subjected to a pressure, which will have the effect of condensing the stock, and bringing it to a substantially uniform thickness, irrespective of variations in the action of the rolls for bringing it approximately to gage.

By providing a presser mechanism acting upon the stock while it is passing from between one pair of calender-rolls to another pair, I am enabled to create a light bank of the surface of the stock which will have the effect of freeing the body of the stock from any imprisoned air, equalizing the thickness of the stock, increasing its density and minimizing a tendency toward the development of surface imperfections. By associating a presser mechanism with each roll intermediate the first and the last roll of the sequence embodied in the calendering machine, I am enabled to secure more satisfactory results, although fairly satisfactory results have been obtained by the use of a single presser mechanism of this character.

In order to adapt the machine for the production of stock of different thicknesses, the presser mechanism or mechanisms above re-

ferred to, are each provided with means whereby they may be set to any desired gage, conforming to the setting of the calendering rolls.

It is desirable in a machine made in accordance with my invention, when the calendering rolls are used in gangs for the purpose of multiplying the product of the machine, to provide suitable stays or reinforcements for imparting the desired rigidity to said presser mechanism, or mechanisms and preventing the warping thereof in a manner to have a tendency to develop irregularity or variances in the the gage of a sheet produced. I have secured the best results by embodying in each of said presser mechanisms, a banking roll adapted to be turned through engagement of the rubber stock therewith, and its movement relatively thereto.

The invention consists in the novel features of construction and combination of parts hereinafter set forth and described, and more particularly pointed out in the claims hereto appended.

Referring to the drawings:

Figure 1 is a view showing diagrammatically, calendering rolls in a four-roll machine, there being associated therewith presser mechanisms, shown in cross-section, for bringing said machine into conformity with my invention;

Fig. 2 is an elevation of one of said presser mechanisms at the back of the machine; and

Fig. 3 a similar view of one of said mechanisms at the front of the machine.

Like numerals refer to like parts throughout the several views.

In the embodiment of my invention shown in the accompanying drawings, the calender rolls, four in number, are shown at 10, 11, 12 and 13. The last of these rolls, 13, has a surface so formed as to bring the finished product to the desired final shape. The various rolls 10, 11, 12 and 13, are all power-driven, preferably at substantially the same peripheral velocity. Between the rolls 10 and 11, I have indicated at 14, a bank of rubber composition to be passed through the machine. The rubber introduced at this point, will be gradually fed from the bank thus provided between the rolls 10 and 11, about the roll 11 to between the rolls 11 and 12 and about the roll 12 to between the rolls 12

and 13, successively, the various rolls being so set as to secure the desired gradual reduction in the thickness of the stock while passing through the machine, to bring it to the 5 desired gage.

In the path of the material, as it passes about the roll 11 and just as it is about to pass between the rolls 11 and 12, is a presser mechanism adapted to act upon said material in a manner to both condense same and remove surface and concealed imperfections therefrom. This mechanism preferably comprises a banking roll 15 mounted in plates 16. To permit adjustment of the 15 roll 15 toward and from the roll 11, I mount the plates 16 in ways 17 formed upon the side frames 18. Acting upon each of the plates 16 is an adjustment screw 19 adapted to engage the removable stop-bar 20 connecting the plates 16. The frames 18 are adjustably mounted upon parallel bars 21 extending transversely of the machine. The plates 16 are provided with the usual parting sections 22 for preventing excessive 25 lateral displacement of the rubber stock passing through the machine. Adjacent the roller 12, I arrange a second presser mechanism, embodying therein a banking roll 23. If desired this roll 23 may extend 30 continuously throughout the entire width of the machine, or of the calender roll coöperating therewith, although preferably I make it in a plurality of independent sections, each of which is mounted by means of suitable 35 ball or roller bearings 24 upon the shaft 25. Each of said sections corresponds in width with that of the strip to be produced. If desired, a single roll 23 may be used, but preferably a machine made in accordance 40 with my invention includes a gang of such rolls 23; and calendering rolls of sufficient width to permit the simultaneous production of a plurality of such strips.

The supports 26 for the shaft 25 are suspended from a bar 27 by means of the brackets 28 and adjustment screws 29 in a manner to permit the adjustment of the various banking rolls 23 toward and from the roll 12 in setting said rolls 23 to 45 form to the setting of the rolls 11 and 12. With a fairly wide machine there is a tendency of the bar 27 to spring or warp intermediate the end supports thereof, and to counteract this tendency, I provide the machine with a stiff brace bar 30, having mounted thereon one or more screw-bolts 31, acting upon the blocks 28 intermediate the ends of said rod 27. In this manner a suitable support for the shaft 25 and the rolls 55 23 intermediate the ends thereof, is provided.

Throughout the machine, suitable lock-nuts are provided to minimize the tendency toward a loss in the adjustment of the machine as a result of the vibrations due to the 55

choking of the machine and resultant strain on the parts.

The supports 26 are each provided with a parting plate 26^a for limiting the lateral displacement of the rubber stock. 70

The operation of the hereinbefore described machine is as follows:

A batch of rubber composition is fed between the rolls 10—11 forming a bank 14, which is gradually passed between said rolls 75 and about the roll 11 to between said roll and the roll 12. As the strip of rubber composition reaches the banking roll 15, the major portion thereof will be subjected to a pressure which will have the effect of condensing it and releasing any air imprisoned therein. The roll 15 being set so as to have the space between same and the roll 11, no greater (and preferably less) than the space between the rolls 10 and 11, a portion 80 of the strip will bank adjacent said banking roll 15, the surplus of stock created at this point being worked into the succeeding stock passing said banking roll. 85

As the strip stock leaves the roll 15, it 90 passes between the rolls 11 and 12 and is further worked and compacted. Thereafter while it is passing about the roll 12, the stock is brought within the operating range 95 of the banking roll 23, where the action described in connection with the roll 15 is repeated.

After leaving the roll 23, the stock passes between the calender rolls 12 and 13 where it receives its final form and finish. 100

By subjecting the sheet or strip stock to the action of a banking roll such as 15 or 23, while it is passing from between one pair of calender rolls to between another pair, I divide the bank which would normally 105 form between said last named rolls, and thus not only secure a more thorough working of the stock, but relieve it from those surface stresses which have a tendency to form surface imperfections. Furthermore, 110 the banking roll will compact or condense the stock just prior to its passing between the adjacent calendering rolls, thus causing greater uniformity in its thickness. 115

By using a roll, 15 or 23, coöperating with a roll or rolls intermediate the first and last rolls of the sequence of rolls embodied in the machine capable of being driven by the engagement of the moving stock therewith, I secure a better compacting action and avoid 120 disturbance of the surface of the strip or sheet as the result of a "drag" at this point.

The adjustability of the rolls 15 and 23, permits these rolls to be properly spaced with relation to their coöperating calender roll and in accord with other adjustments in the machine. 125

By arranging the banking rolls in gangs, the output of the machine may be multiplied.

It is not my intention to limit the invention 130

tion to the precise details of construction shown in the drawings, it being apparent that such may be varied without departing from the spirit and scope of the invention.

5 Having described the invention, what I claim as new and desire to protect by Letters Patent is:

1. A machine for treating rubber, embodying therein a sequence of calendering rolls 10 adapted to act successively upon the stock passing through the machine, and a non-driven presser mechanism having a convex surface coöperating with one of said rolls intermediate the first and last rolls of the 15 sequence, whereby the stock is compacted and banked as it is about to pass between succeeding calendering rolls.

2. A machine for treating rubber, embodying therein a sequence of calendering rolls 20 including a plurality of rolls intermediate the first and last rolls of the sequence, and a plurality of presser mechanisms having convexed surfaces coöperating with said intermediate rolls respectively, whereby the stock 25 is compacted and banked as it is about to pass between succeeding calendering rolls.

3. A machine for treating rubber, embodying therein a sequence of calendering rolls adapted to act successively upon the stock 30 passing through the machine, a non-driven presser mechanism having a convexed surface coöperating with one of said rolls intermediate the first and last rolls of the sequence, whereby the stock is compacted and 35 banked as it is about to pass between succeeding calendering rolls, and means whereby said presser mechanism may be adjusted toward or from its coöperating roll.

4. A machine for treating rubber, embodying therein a sequence of calendering rolls 40 including a plurality of rolls intermediate the first and last rolls of the sequence, a plurality of presser mechanisms having convexed surfaces coöperating with said intermediate rolls respectively, whereby the stock 45 is compacted and banked as it is about to pass between succeeding calendering rolls, and independently operating means whereby each of said presser mechanisms may be adjusted toward or from its coöperating calendering rolls.

5. A machine for treating rubber, embodying therein a sequence of calendering rolls adapted to act successively upon the stock 55 passing through the machine, and an idler banking roll mounted adjacent and coöperating with one of said rolls intermediate the first and last of the sequence whereby the stock is compacted and banked as it is about 60 to pass between succeeding calendering rolls.

6. A machine for treating rubber, embodying therein a sequence of calendering rolls including a plurality of rolls intermediate the first and last rolls of the sequence, and a 65 plurality of banking rolls coöperating with

said intermediate rolls respectively, whereby the stock is compacted and banked as it is about to pass between succeeding calendering rolls.

7. A machine for treating rubber, embodying therein a sequence of calendering rolls adapted to act successively upon the stock passing through the machine, an idler banking roll mounted adjacent and coöperating with one of said rolls intermediate the first 70 and last of the sequence whereby the stock is compacted and banked as it is about to pass between succeeding calendering rolls, and means whereby said banking roll may be adjusted toward or from its coöperating 75 calendering roll.

8. A machine for treating rubber, embodying therein a sequence of calendering rolls including a plurality of rolls intermediate the first and last rolls of the sequence, a plurality 80 of banking rolls coöperating with said intermediate rolls respectively, whereby the stock is compacted and banked as it is about to pass between succeeding calendering rolls, and independently operating 85 means whereby each of said banking rolls may be adjusted toward or from its coöperating calendering roll.

9. A machine for treating rubber, embodying therein a sequence of calendering rolls 90 adapted to act successively upon the stock passing through the machine, an auxiliary idler roll mounted adjacent and coöperating with one of said rolls of the sequence, and means for positively driving said last mentioned roll.

10. A machine for treating rubber, embodying therein a pair of calendering rolls, one of said rolls having a circumferential depression for coöperating with said other roll to define the sectional contour of the rubber passing therebetween, an auxiliary idler roll adjacent and coöperating with the other roll of said pair, and means for positively driving said pair of rolls.

11. A machine for treating rubber embodying therein a pair of calendering rolls and a non-driven presser mechanism having a convexed surface coöperating with one of said rolls whereby the stock is compressed 105 previous to its passage between said calendering rolls.

12. A machine for treating rubber embodying therein a pair of calendering rolls and an auxiliary idler roll mounted adjacent 110 and coöperating with one of said calendering rolls whereby the stock is compacted previous to its passage between said calendering rolls.

13. A machine for treating rubber embodying therein a pair of calendering rolls, a non-driven presser mechanism having a convexed surface coöperating with one of said rolls whereby the stock is compressed 115 previous to its passage between said calendering rolls.

dering rolls and means whereby said presser mechanism may be adjusted toward or from its coöperating roll.

14. A machine for treating rubber embodying therein a pair of calendering rolls, an auxiliary idler roll mounted adjacent and coöperating with one of said calendering rolls whereby the stock is compacted previous to its passage between said calendering rolls, and means whereby said idler roll may be adjusted toward or from its coöperating calendering roll.

15. A machine for treating rubber embodying therein a pair of calendering rolls, a presser mechanism having a convex surface coöperating with one of said rolls whereby the stock is compressed previous to its passage between said calendering rolls, and a parting plate for the calendering rolls positioned at each end of the presser mechanism.

16. A machine for treating rubber embodying therein a pair of calendering rolls, an auxiliary roll mounted adjacent and coöperating with one of said calendering rolls whereby the stock is compacted previous to its passage between said calendering rolls, and a parting plate for the calendering rolls positioned at each end of the auxiliary roll.

30 17. A machine for treating rubber embodying therein a pair of calendering rolls, a pair of parting plates for said calendering rolls, and a presser mechanism mounted on said plates coöperating with one of said rolls whereby the stock is compressed previous to its passage between said calendering rolls.

18. A machine for treating rubber embodying therein a pair of calendering rolls,

a pair of parting plates for said calendering rolls, and a roll journaled in said plates coöperating with one of said calendering rolls whereby the stock is compacted previous to its passage between said calendering rolls.

19. A machine for treating rubber embodying therein a pair of calendering rolls, a presser mechanism having a convex surface coöperating with one of said rolls whereby the stock is compressed previous to its passage between said calendering rolls, a 50 parting plate at each end of the said mechanism for limiting the width of the material passing said mechanism.

20. A machine for treating rubber embodying therein a pair of calendering rolls, a presser mechanism having a convex surface coöperating with one of said rolls whereby the stock is compressed previous to its passage between said calendering rolls, and a parting plate for said mechanism and calendering rolls at each end of the said mechanism for limiting the width of the material passing said mechanism and calendering rolls.

21. A machine for treating rubber embodying therein a pair of calendering rolls, a presser mechanism coöperating with one of said rolls whereby the stock is compressed previous to its passage between said calendering rolls, a parting plate positioned at 70 each end of the presser mechanisms, and means for adjusting the parting plates relative to the calendering roll with which the said mechanism coöperates.

Signed at Detroit, county of Wayne, State 75 of Michigan, this 12th day of July, 1917.

WILLIAM KEARNS.
